UNITED STATES PATENT OFFICE.

JOHN J. BURK, OF BUFFALO, NEW YORK, ASSIGNOR OF ONE-HALF TO
EDWARD M. JEWETT, OF SAME PLACE.

NAIL-DRIVING MACHINE.

SPECIFICATION forming part of Letters Patent No. 252,834, dated January 24, 1882.

Application filed October 3, 1881. (No model.)

To all whom it may concern:

Be it known that I, JOHN J. BURK, a citizen of the United States, residing in Buffalo, in the county of Erie and State of New York, have 5 invented certain new and useful Improvements in Nail-Driving Machines, of which the following is a specification.

The object of my invention is to produce a reliable and rapid means for nailing hoops, 10 boxes, &c., and clinching the nails when driven; and it consists of the following elements: first, an oscillating drum or box operated by connections with the foot-step, for holding the 15 nails and dropping them into the usual inclined guideways, in combination with a separating device, from which the nails are delivered one at a time to the nail-receiving jaws; second, a nail-driving mechanism having an adjustable device for limiting its movement downward, 20 in combination with a foot-step and its connections and operating mechanism; third, the nail receiving and guiding mechanism, whereby the nail is started into the wood before the 25 lower jaws separate at the bottom, so that the end or point of the nail is guided to the exact point required, and is consequently always driven straight; fourth, an inclined vertically-adjustable anvil, by which the point of the 30 nail is turned and clinched across the grain of the wood when driven, all of which will be more clearly hereinafter shown and described by reference to the drawings, in which—

Figure 1 is a side elevation of the machine complete. Fig. 2 is a front elevation; Fig. 3, 35 an enlarged front elevation of a portion of the machine. Fig. 4 is an enlarged sectional elevation of the guiding-jaws. Fig. 5 represents an enlarged top view of the receiving-jaws, and Fig. 6 is a top view of the nail-guiding 40 jaws.

The frame of the machine consists of the upper part, A, the two front legs, a, and a back leg, a', to which a treadle, a², which is forked at the end, is secured by a bolt, b. (See Figs. 45 1 and 2.) To the rear part of the frame is rigidly fastened, by bolts or other well-known means, two bars, B, and the front of said frame is connected with two vertical rods or bars, B',

the bars B and B' being connected at the top by two horizontal bars, B².

C represents the inclined slotted guideway for the nails. It is supported by the frame C⁴, which is supported at the rear end by two jointed or swinging arms, c. The front end, B³, is connected with or forms a portion of the 55 part C', and is provided with holes c', (see Fig. 5,) through which the rods B' pass, so that the front end of the inclined guideways C and the frame C⁴ have a free up-and-down movement on said rods, while the rear portion swings on the joint c'.
50

To the rear portion or upper part of the guideways and frame C⁴ is connected the nail box or drum C². It is supported on an axis or shaft, c³, within a hopper, C³, having inclined sides d, so that the nails, as they drop down, will be guided into the opening D in the inclined guideways. (See Fig. 3.) The nail-box C² is provided with a ratchet-wheel, e, pawl e', and arm e², which arm is rigidly fastened to the shaft c³.
55

To the arm e² is jointed a rod, D', (see Figs. 1 and 2,) by a bolt, d', its opposite end being jointed to a frame, D², which frame is supported at the back end so as to swing on two jointed 65 arms, E, one on each side of the inclined guideway-frame C⁴. Its front end embraces the nail-driving rod F and rests on a shoulder, F', which shoulder is made adjustable by a set-screw, f. The frame D² is connected by a forked piece, 70 F², and a rod, f', with the treadle or foot-piece a². It will now be seen that a movement of the treadle downward will cause the several parts named to move into the position shown by the dotted lines d³ in Fig. 1, and that the nail drum 75 or box will be moved one notch forward, and that a reverse movement of the foot-step will cause the pawl to move back so as to catch another notch in the ratchet-wheel e.
80

While the machine is operating the nails 90 drop out of the holes f³ in the nail-box (see Fig. 2) into the opening D, which is just wide enough to catch the heads and let the rest pass through. The nails slide down the slide-way until one—i, for instance, see Fig. 3—95 strikes the first separating-bar, G, when it is

- stopped, and the rest that follow lie against each other. The bar G passes through the side of the frame C⁴, which acts as a journal for it, and through one side of the inclined guideway.
- 5 It has both a longitudinal and a turning movement by means of an arm, G², a pin, F⁴, on the side of the forked piece F², and an inclined projecting piece, G³, on the side of the frame C⁴, the bar G being held or drawn inward by 10 a spiral spring, H, the arrangement being such that when the foot-step a² is moved downward the pin F⁴ also moves down against the arm G² and causes it to turn the bar G, and the arm G², while turning, moves against the inclined face of the projecting piece G³, thereby 15 causing the bar G to move longitudinally outward, so as to allow a nail to pass by the end of it and against the bar or pin G', which has in the meantime moved against or inward, so 20 as to prevent the nail from passing. The bar G' passes through the opposite side of the frame C⁴ and through one side of the inclined guideway, (see Fig. 3,) and is bent upward and then in, so as to pass again through the side 25 of the frame C⁴, by which arrangement it is prevented from turning, while it has a free longitudinal movement and is kept in position one way by the spring H, which is also connected to it by means of an arm, I, (see Figs. 30 2 and 3,) and is forced the other way or outward by the upward movement of the treadle and the inclined bar H', which is fastened to the opposite side of the forked portion F², so as to move up and down with it. (See Figs. 2 35 and 3.)
- It will be seen from this construction that as the treadle is forced down by the foot the bar or pin G will move out and let the nails slide down the incline against the bar or pin 40 G', which has at the same time moved inward, and that when the movement of the treadle a² is reversed by means of the spring I', when the pressure of the foot is taken off from it the bar G will move inward and pass in between 45 the nail resting against the pin G' and the nail above it, thereby separating it from the rest. At or near the same time the pin G' is moved out, so that the separated nail can drop or pass farther down the inclined guideways.
- 50 It will be noticed that the turning movement, in addition to the longitudinal movement, renders the bar G more sure to enter between and separate the nails. The nail, after leaving the pin G', passes down into the nail-receiving jaws J, which are arranged so as to 55 swing on pins or bolts J', (see Figs. 3 and 5,) and are kept closed by a spring, g, so that only room enough is left for the body of the nail to pass into the opening J², (see Fig. 3,) where it 60 is held loosely suspended by the head. In this position the end B³ of the inclined guideway, which has a movement up and down from B³ to the pin B⁴, has been forced up by the upward movement of the forked piece F², as it 65 comes in contact with it in its upward move-

ment at or about the point h, (see Fig. 1,) and it falls again by its own weight when the part F² descends. The nail being held loosely by the head, the body assumes a vertical position with the point downward, and when the foot-step is forced down the nail-driver F is also brought down, and also the part B³, which brings the point of the nail over or within the hole K in the piece K'. (See Figs. 3 and 4.) The nail-driver F, when it strikes the head of 70 the nail, forces the receiving-jaws J open and the nail through them or between them into the guiding-jaws L L, (see Figs. 3 and 4,) which jaws are closed, as shown by the dotted lines n in Fig. 3, so that the hole between them in 80 that position is a tapering hole, smaller at the bottom, so that the nail is guided into the exact point required. As the nail-driver completes its movement downward the guiding-jaws are opened into the position shown in 85 Fig. 4 and the nail is driven through the material to be nailed—a hoop, for instance, shown by dotted lines m in Fig. 2—and the point of the nail strikes the inclined anvil N and is turned over or clinched in the direction of the 90 incline. When the nail-driving bar is withdrawn the jaws L L are again forced together by the springs r r. (Shown in Fig. 4.) The parts K' K² are in one piece, and are provided with holes similar to the holes c', (shown in 95 Fig. 5,) so that the rods or bars B' can pass through. The pin B⁴ (shown in Fig. 3) limits the movement of K' upward. The anvil N is made vertically adjustable by means of the set-screws r' r', (see Figs. 1 and 2,) and the 100 movement of the nail-driving bar F is limited by the nut S. (See Figs. 1 and 2.) The vertical movement of the end B³ of the inclined guideway is also limited by the bolts T and the pin B⁴, which also limits the upward movement of the part K'. (See Fig. 3.) The inclined anvil N is adjusted so that the article to be nailed may be easily placed between it and the lower part of K², and when the nail is being driven the part K' K² moves down on 105 the rods B' only far enough to tightly clamp and hold the article to be nailed.

I claim as my invention—

1. In a nail-driving machine, a separating nail-bar, G, having both a longitudinal and an 115 oscillating movement, in combination with the arm G², pin F⁴, inclined projecting piece G³, spring H, and their operating mechanism, substantially as and for the purposes described.

2. The oscillating nail-box F² and inclined 120 guideway C, in combination with the longitudinally movable and oscillating nail-separating bar G and the separating-bar G', with their operating mechanism, substantially as specified.

3. The inclined guideway C, in combination with the vertical rods B', end piece, B³, nail-receiving jaws J J, and spring g, for the purposes described.

4. The parts K' K², provided with the open- 130

ing K, in combination with the nail-guiding jaws L L and springs r r, for the purposes described.

5. The combination of the nail-driving bar F and its operating connections D², F², f', and a² with the vertically-adjustable anvil N, for the purposes specified.

6. The inclined guideway C, provided with

the end piece, B³, adapted to move up and down on the rods B', in combination with the 10 part K' and the bolts T, for limiting the vertical movement of the guideway C, as set forth.

JOHN J. BURK.
